UNITED STATES PATENT OFFICE

2,206,713

PHOTOELECTRIC APPARATUS

Kenneth T. Bainbridge, New York, N. Y., assignor
to General Electric Company, a corporation of
New York

Application August 28, 1929, Serial No. 389,066

8 Claims. (Cl. 250—41.5)

The present invention relates to light-sensitive apparatus and more particularly to photoelectric devices.

Photoelectric tubes are usually divided into two groups depending upon the manner in which the photoelectrons move toward the positive electrode. In one group may be placed those devices which operate on a pure electron basis as when the envelope is highly evacuated and the other group 10 may consist of those devices which depend upon ionization between the electrodes in which case, the envelope contains a substantial amount of gas. Photoelectric tubes of the highly evacuated type are utilized in systems where uniformity of 15 operation and rapidity of response are necessary as in the case of rapid variations of light but have the disadvantage of producing photocurrents of small magnitude calling for one or more stages of amplifying accessories in order to derive a current of practical amount. On the other hand, while the gas-filled tubes give photocurrents of a larger order than those of the pure electron discharge type, hence necessitating less amplification if any, they have the disadvantage of a non-linear response when considered in terms of 20 photocurrent per unit of light intensity and in addition may offer a time lag when dealing with light of an undulating character as in television. Moreover, in case the gaseous photoelectric devices are operated at potentials which produce 25 substantial ionization, the light sensitive surface may be destroyed by positive ion bombardment.

An object of the present invention is to provide a photoelectric tube which will combine the uniformity and rapidity of response peculiar to the pure electron discharge type with the desirable feature of producing a photocurrent of substantial magnitude as found only in the prior art gas-filled tubes without introducing the disadvantages 30 usually inherent in the latter. The object is thus to combine the desirable features of both types of tube, at the same time eliminating the undesirable properties. In carrying out the invention, I propose to utilize an envelope devoid 35 of gas and to increase the current-carrying capacity of the device by the use of secondary emission phenomena. The invention will be better understood when reference is made to the following description and the accompanying 40 drawing. The figure represents a perspective view in elevation of the improved photoelectric tube, connected in a circuit for explanatory purposes.

In the drawing, numeral 1 designates a highly 45 evacuated envelope terminated by a reentrant

stem and press 2. In the press there are fused three rigid wires leading to a plurality of electrodes 3, 4 and 5. These electrodes are shown as rectangular in shape, extending in the same direction and arranged in vertical planes when referred to the tube position as shown, the two outer members being angularly disposed with respect to one another in the horizontal plane and having the central electrode arranged preferably equidistantly between the outer members. 5 The electrodes 3 and 5, which may be termed for convenience, primary cathode and secondary cathode respectively, are constituted of a solid member while the central electrode, which may be considered a collector or anode, takes on the general form of a grid with fine wires and a relatively wide mesh. The cathodes 3 and 5 are each rendered light-sensitive although as will be explained hereinafter, it is necessary for satisfactory operation to provide a photoelectric surface only on the more negative cathode, i. e. electrode 3. In the preferred arrangement the cathodes are constituted of a base metal such as nickel or copper which may be silver-plated preferably apart from the envelope in which they are to be 10 employed by any well known process e. g. by electro-plating, chemical deposition, or electrical sputtering as disclosed and claimed in the Ruggles Patent #1,568,694. The silver coating is 15 oxidized, preparatory to receiving the light-sensitive material, by immersing the plates in an oxidizing atmosphere preferably confined in envelope 1 or a separate bulb and glowing the electrodes by applying high voltage thereto from a 20 spark coil. The oxidation may also be produced 25 by applying a high voltage direct current derived from a suitable rectifier set. In either case, the depth of the oxide layer may be controlled by the duration and intensity of such treatment. When the desired degree of oxidation has been 30 effected, the plates, if not already placed in position, may be mounted in the envelope 1 together 35 with the grid-like anode 4. In order to sensitize the silver or other metallic oxide surface on the cathodes, caesium or other suitable alkali vapor is introduced into the envelope either by distillation from a side tube or from pellets heated 40 by high frequency currents or in any other well known manner. The caesium vapor condenses 45 on each of the cathodes and the anode but sticks 50 only to the cathode surfaces inasmuch as the oxide layer thereon serves as a binder or a glue. It has been found that when the anode is fabricated of nickel which does not oxidize readily, 55 or of molybdenum which oxidizes to produce an

oxide which does not combine in a substantial degree with caesium, the anode surface remains practically insensitive to light. The excess alkali material preferably is removed from the envelope in any suitable manner, for example, by distillation and evacuation of the excess vapor to the manifold, in order to lend to the device uniformity of operation as disclosed and claimed in my prior application Serial No. 244,533 which has matured 5 into Patent No. 1,901,577, granted March 14, 1933.

The primary cathode 3 and the anode 4 may be connected to a source of direct current 6, the member 4 being positive while the secondary cathode 5 is connected to an intermediate terminal 7 in the potential source. This terminal preferably should be at such a position that the potential difference between electrodes 3 and 4 is of the order of several times the potential difference between electrodes 4 and 5, for example, 10 ten times. It will be noted that the cathodes 3 and 5 are both negative with respect to the anode or collector 4. When a light beam from an external source indicated generally by the cross 8 impinges on the primary cathode 3, the latter 15 loses electrons which are accelerated in the electrostatic field between this electrode and anode 4 to a velocity equivalent to the total voltage of battery 6 which may be of the order of several hundred volts. A substantial part of these electrons 20 pass through the mesh of the anode 4 and impinge on secondary cathode 5 with an impact sufficiently great to give rise to secondary electrons in considerable numbers at the surface of electrode 5. These electrons are propelled to 25 ward the anode or collector 4 under the influence of the electrostatic field between the secondary cathode and the more positive collector. While this field is in the opposite direction to the field between electrodes 3 and 4, it is apparent that 30 its retarding effect on the primary electrons travelling from the cathode 3 is small because the potential difference between electrodes 3 and 4 is many times the potential difference of the decelerating field between electrodes 4 and 5. It 35 is evident that the potentials assigned to the various electrodes may be such as to produce a large preponderation of the secondary electrons at the surface of the secondary cathode over the number of primary electrons initiated at the primary cathode by light activation and that this 40 electron preponderation may be utilized in an external circuit by way of photocurrents of augmented amplitude. This circuit normally would be connected between electrodes 4 and 5 at the 45 place indicated by the pair of open terminals. In each of the electrode leads, there may be inserted current measuring devices 9, 10 and 11 to 50 determine when the greatest sensitivity of operation is reached in terms of magnitude of photocurrent as the inter-electrode voltages are 55 regulated. It is obvious that the ammeter 9 will register the total primary electron current leaving the surface of cathode 3, the ammeter 10 indicating the combined secondary photocurrents 60 and a portion of the primary photocurrents depending upon the fineness of the grid and other factors. The ammeter 11 will read the difference 65 between the remainder of the primary electron current which reaches the surface 5 and the combined secondary electron current and photocurrent leaving this surface. In order further to 70 enhance the primary and secondary electron flow, the plates 3 and 5 may be arranged angularly with respect to one another thereby to obtain a multiple reflection effect of the light beam 75

between these plates. It is apparent that the secondary cathode when acted upon by the light reflected by the primary cathode gives rise to primary electrons additional to those formed at the cathode 3 and which augment to a certain extent the number of electrons leaving the cathode 5 and travelling toward anode 4.

From the foregoing it is evident that I have disclosed a novel form of photoelectric tube which operates on a pure electron basis, hence 10 offers all the advantages of this type of device, at the same time, is capable of producing photocurrents of several times the amplitude of those generated in the prior art tubes which depend solely on primary electron flow. The increased 15 order of photocurrent amplitude may, by proper tube design and regulation of the applied voltages, come within the range of currents heretofore reached solely in gas tubes, the advantage being obtained without introducing the deleterious effects which usually accompany tubes of the gas type. Inasmuch as the production of the secondary electrons at the surface of secondary cathode 5 is dependent upon the impingement therewith of the primary electrons produced at 20 cathode 3 and further since the primary electrons are controllable by the light beam, it is apparent that the secondary photocurrents are also under the positive control of the light.

It will occur to those skilled in the art that the 30 secondary cathode need not have a highly light-sensitive surface but may consist simply of ordinary metal, in which case the increase in current due to multiple reflection would not be quite so pronounced, although under certain conditions 35 as when the secondary cathode has high reflectivity, the output current may actually be greater than in a case where this cathode is provided with a surface of relatively high light sensitivity. It is apparent that in the case of a cathode having a specular non-photosensitive surface, most 40 of the light incident thereon would be reflected without the production of photoelectrons at this surface and the reflected light would give rise to photoelectrons on the surface of the primary cathode additional to those produced by the direct light beam which may increase the total 45 measured current in circuit 10. The use of a secondary cathode which is not light-sensitive 50 presents an advantage in that the choice of materials insofar as the secondary emission is concerned need not be restricted to a highly photosensitive substance, hence materials which are particularly well suited for emitting secondary electrons may be employed, such as barium oxide 55 (BaO) or metallic barium (Ba) applied as a coat to the foundation metal. Accordingly, my invention is not to be limited to any particular class of materials for the secondary cathode member 5 but is sufficiently broad to cover efficient secondary emission surfaces with or without the quality of high photosensitivity. It is also apparent that the electrodes 3, 4 and 5 may take on various shapes and arrangements, for example, the primary cathode may consist of a 60 semicylinder with a secondary cathode in the form of a cylinder of smaller diameter than the primary cathode and surrounded by a helical grid-like anode, all concentrically arranged.

What I claim as new and desire to secure by 70 Letters Patent of the United States is:

1. In combination, a tube comprising an evacuated envelope containing a primary cathode having a light sensitive surface, a light source 75 impinging upon said surface, a secondary cath-

ode and an anode, said electrodes extending in the same direction and the cathodes being inclined angularly with respect to one another whereby the light impinging on the primary cathode is given a multiple reflection effect between the cathodes, a source of electromotive force connected between the cathodes of such strength and polarity that the photo-electrons are impelled toward the secondary cathode with a velocity sufficient to produce secondary electrons, a source of electromotive force connected between the secondary cathode and the anode adapted to impel the secondary electrons toward the anode and an output circuit connected between the secondary cathode and the anode.

2. In combination, a tube comprising an evacuated envelope containing a primary cathode, a secondary cathode and an anode inclined angularly with respect to one another, each of said cathodes having a light-sensitive surface, a light source for activating said surface whereby photo-electrons are produced, means for accelerating the photoelectrons between the cathodes with a velocity sufficient to produce secondary electrons, means for impelling the secondary electrons toward the anode and an output circuit connected between one of the cathodes and the anode.

3. A photoelectric tube comprising an envelope containing a pair of plate-like electrode elements positioned in non-parallel relationship, said electrode elements being coated with light sensitive material on faces adjacent each other, and a grid-like anode element through which electrons may pass interposed between said plates.

4. A photoelectric tube comprising an envelope, a pair of bi-dimensional light sensitive members supported therein in inclined relationship relative to each other and having thereon a coating of light-sensitive material adapted to release photo-electrons when subjected to light, means includ-

ing an electron permeable electrode interposed between said light sensitive members for accelerating the photoelectrons from one of said light sensitive members toward the other of said members with a velocity sufficient to produce secondary electrons, and electrical connections to said accelerating means and one of said light sensitive members.

5. A photoelectric tube comprising an envelope, electrodes therein including a plurality of bi-dimensional light sensitive members each adapted to release photoelectrons when subjected to light, means including one of said electrodes for accelerating the photoelectrons from one of said light sensitive members toward another of said members with a velocity sufficient to produce secondary electrons, and electrical connections to said accelerating means and one of said light sensitive members.

6. In combination, a photoelectric tube comprising an envelope containing a pair of angularly positioned light-sensitive members, an electron permeable anode interposed therebetween, and means for charging said electrode and one of said light-sensitive members positive with respect to the other of said light-sensitive members.

7. A phototube comprising a light sensitive photocathode, a solid plate secondary emitter electrode positioned to receive photoelectrons emitted from said photocathode, and a grid-like collector electrode surrounding said secondary emitter electrode.

8. A phototube for utilizing secondary emission to produce primary emission amplification comprising a light sensitive primary electron emitting photocathode, a secondary electron emitting cathode, and a collector electrode surrounding said secondary emitter cathode for collecting said primary and secondary electrons.
